CLAIM

I claim the ornamental design for a cosmetic holder, as shown and described.

DESCRIPTION

The present design application is related to two design applications, of the same title, which are filed concurrently herewith Ser. Nos. 29/332,016 and 29/332,018.

FIG. 1 is a front perspective view of my new and original ornamental design for a cosmetic holder, wherein the rear perspective view is identical to the front perspective view shown;

FIG. 2 is a front elevation view thereof, wherein the rear elevation view is identical to the front elevation view shown; and,

FIG. 3 is a top plan view thereof.

The bottom of the design is flat and devoid of surface ornamentation, and portions of the design that are not shown in the drawings form no part of the claimed design. The broken lines indicate bounds of the claimed design.

The broken lines shown in the drawings illustrate interior portions and form no part of the claimed design.
